FORM TIE FOR WALL STRUCTURES

John L. Bracewell, Shreveport, La.

Application September 12, 1947, Serial No. 773,688

3 Claims. (CL 25-131)

1

My invention relates to form ties for wall structures, but more particularly to a form and wall tie for the use and construction of concrete or other plastic formed walls in which temporary molds or forms are employed to receive the plastic material which is subsequently permitted to set and harden to form the finished wall or cast.

The hereinafter described subject matter is intended to constitute a continuation-in-part of my parent application filed July 29, 1946, and bearing the Serial Number 687,037, now abandoned.

One of the objects of my invention is to provide a form holder and wall tie which may be made in large quantities at a relatively small cost, and which may be used in the temporary erection of sectional, demountable form structures or mold boards.

Another object of my invention is to provide a form holder that will resist both the compressive and expanding thrusts of a wall form, such as is occasioned when tying the two side forms together to form a mold for a plastic material such as concrete, or the like.

Another object of my invention is to provide a metallic, cylindrical tube, arranged to resist the compressive thrusts upon erecting the two sides of a concrete wall form, the tube being so designed that it will become part of the wall itself.

Other objects and advantages of my invention will be found in the following detailed description when viewed together with the accompanying drawings in which:

Figure 1 is a vertical sectional view through a portion of a concrete wall structure showing an embodiment of my invention;

Fig. 2 is a broken sectional view showing a preliminary step in applying my invention to a concrete form;

Fig. 3 is a sectional view showing the manner of aligning the holes for the tie rods in a concrete structure;

Fig. 4 is an enlarged perspective view of the collar element of my invention;

Fig. 5 is a partially broken view showing the spacer element of my invention;

Fig. 6 is a partially broken view showing a manner in which my invention may be used in association with prefabricated form sections, the assembly being lowered over an existing footing and upwardly extending reinforcing rods;

Fig. 7 is a longitudinal sectional view showing my invention in a form tie in modified form;

Fig. 8 is an end view of the assembled tie looking in the direction of line 8-8 of Fig. 7;

Fig. 9 is a perspective view of a modified tie rod

adapted for use in the form illustrated in Fig. 7; and

Fig. 10 is a perspective view of the resilient collar member used in the modified device; and

Fig. 11 shows the method of assembling the spacer member into the collar at one side of the inner face of one form preparatory to the movement of the opposite form into aligned position

with the projecting end of the spacer member.

Referring to Fig. 1 of the drawings, I have provided the usual wall form consisting of side members 10, 10, studs 11, and battens 12. After

setting this arrangement, concrete is poured

between the members to form the wall 13.

My improved wall tie consists of a tie rod 14 having adjustable securing collars 15, the tie rod 14 being adapted to be placed through the side members 10 of the wall 13 to prevent the wall from spreading when poured.

Many times upon erecting a wall, the plastic material used does not have sufficient weight nor strength to overcome an inward misalignment of the forms due to the excessive pressure of the tie rods; hence a slight concave surface is left on either one or both sides of the finished wall when the forms are removed. This condition greatly handicaps the attaching of subsequent woodwork or other fixtures which depend largely upon the wall's being substantially straight and square for their erection or installation.

To overcome this serious defect in wall construction, I have provided a collar 16, having mounting holes 17, which collar is adapted to be secured to the side members 10 and arranged to receive a metallic spacer or sleeve 18.

My spacer 18 comprises a metallic tube of a diameter sufficient to be slidably inserted into the collar member 16. Embracing the tube portion of my spacer 18, at a distance from each end comparable to the thickness of my collar member 16, I have provided an integrally attached flange 19 which is adapted to form a stop against the face portion of the collar 16. Thus, when the two sides of the form are pulled together by the tie rod 14, the spacer member 18 will separate the two sides to an exact, desired distance, and upon removal, will leave a finished wall with smooth, parallel sides.

It will be noted that the outer periphery of the tube portion of my spacer member 18, between the two flanges 19, has been scored, grooved or serrated, thus presenting better adhesive qualities to a concrete which is subsequently poured into the forms. These serrations also provide a place for the steel worker to tie the binding wires to the reinforcing rods; that is, a reinforcing rod

may be brought into contact with my spacer 18, and when tied or laced with wire, the annular grooves or serrations will prevent the wire from slipping along the spacer and occasionally allowing the form to slip out of line, and also prevent the steel reinforcing rods from leaning toward one of the outside wall forms.

My improved wall tie is installed as shown in Figs. 2 and 3 of the drawings. After the side members 10 of the form have been attached to the studs 11, I simply strike chalk lines 20, forming any desired size of squares on the inside surface of the side members 10. Over the intersection of these chalk lines 20, I attach the collars 16, using ordinary nails 21 through the mounting holes 17.

As can be seen in Fig. 4, the collars 16 are of rectangular shape and are preferably made of some cast metal. Each collar 16 is further provided with four side faces which recede from the outside face of the collar, thus forming sufficient draft for its easy removal from the finished concrete wall. I have also provided on these four faces small projections 22 which leave recesses in the finished wall suitable for grouting purposes.

Through the center of the collar element 16, I have provided a hole 23 of sufficient diameter to slidably receive the ends of the tubular spacer members 18.

When the desired number of collars have been attached to the side members 10 of the form, I use the intersecting points of the chalked lines as a mark, and with an ordinary wood bit 24 drill a clearance hole for the tie rod as shown in Fig. 2.

After drilling all of the clearance holes for the tie rods in one of the side members of the form, I then insert one end of the spacer members 18 into the holes 23 of the collars 16, and then place the other collars on the other ends of the spacers as shown in Fig. 11.

The opposite side of the form 10' is then brought against the projecting collars and temporarily braced. Since the bearing surface in the collar is sufficient to support the spacer members 18 in a horizontal position, it is not necessary to nail the opposite collars to the side members 10'.

As can be seen in Fig. 3, I use the same wood bit 24 directed from the outside of the form, and using the inside wall portion of the spacer member 18 as a guide, bore the opposite clearance hole for the tie rod 14.

Thus, upon tightening and securing the adjustable collars 15 against the washers 25, the two side forms are brought together, bringing the face of the collars 16 against the flanged stop members 19 in the various spacers and the side forms to an exact distance apart. After removing the forms, the remaining concrete wall will have parallel sides.

Upon dismantling the forms after the concrete has hardened, the adjustable collars 15 are loosened and the tie rods 14 are removed. The battens 12 are taken off and the side members 10 and 10' and the studs 11 are taken down. Since the collar members 16 have been previously coated with a grease preparation and provided with sufficient draft, they may easily be removed from the wall 13, leaving a construction as shown in the upper portion of Fig. 1.

Into the open ends of the tubular spacers 18 a wooden plug 26 may be driven which serves as a ground for attaching partitions, fixtures, molding, or any additional construction where grounds are necessary.

In the recess left in the concrete wall by the removal of the collar members 16, I simply apply a grout 27, thus finishing both sides of the wall smooth.

It will be noted that my tubular spacer member 18 may be used as a chase for wiring conduit, piping or the like, or for any purpose that might be suitable for its inside diameter. It will be further noted that these additional uses of my wall tie will not interfere with its general purpose as described.

Reference to Fig. 6 of the drawings I have shown another use of my improved wall tie. In this instance the side members of the forms have been prefabricated and my invention used to separate the side members of the form at a desired wall thickness, the collars 16 on both sides being securely attached as formerly described, and the entire assembly lowered over upwardly extending reinforcing rods in an existing footing 28.

The novel feature in the use of my invention as shown in Fig. 6 is that the reinforcing rods 29 may be either bent over the spacer members 16 or may be tack-welded to the same, thus supplying additional reinforcement to the finished wall.

In Fig. 7 the spacer element 18' is shown in modified form. This modified spacer 18' is provided with a slightly restricted opening at each end having slots 34 formed therein as shown in Fig. 8 to permit the entrance of the modified tie rod 30. The tie rod 30 is provided with a rectangular head 31 arranged to be slidably inserted into the spacer 18' through the slots 34. This type of construction is particularly advantageous where an excavated foundation trench is made too narrow to permit the insertion or withdrawal of a long tie rod through the wall. In such case, an operator would use a pair of the modified tie rods 30, inserting the heads 31 thereof through the slots 34 of the various spacers 18' and turn the rods 30 approximately ninety degrees to right or left to where the back portion of the heads 31 would come in contact with the inner wall surface of the restricted ends of the spacer members 18'. The operator would then be able to jack the rods tight and retain them in this position by setting the restraining collars 15. After the wall has been poured and set, the form may be easily dismantled by loosening the collars 15 and slipping the heads 31 of the tie rods 30 out of the slots 34.

Another modification of the above mentioned structure is the application of a resilient washer 32 which is provided with a square hole 33 adapted to be slipped over the collar 16 as the form is assembled. This washer 32 is preferably of rubberized material and of the same thickness as the collar 16.

When the concrete is subsequently poured between the forms, the added weight will simply contract the resilient washers 32, yet still allow them to be easily removed when the wall has set and the forms are taken down. While it is not essential, it is preferred that the washers 32 be coated with a grease preparation before use to insure their easy removal from the wall. After removal of the forms 10 and 10', the recesses in the finished wall left by the collars 16 and washers 32 may be grouted or plugged as described in the use of the preferred form of my invention.

While I have described my invention in detail both in preferred and modified form, it is to be understood that other changes and alterations may be made without departing from its

spirit and scope as defined by the following claims.

I claim:

1. A mold structure comprising a pair of spaced mold forms, one of said forms having an apertured plate secured to the inner face thereof and defining a central opening therethrough, a similarly apertured plate adapted to be aligned with the opening of the aforesaid plate and disposed in contact with the inner face of the other of said mold forms, a spacer member having a tubular body structure extending linearly between said mold forms and terminating at opposite ends in integral flanges tapered outwardly from said tubular body structure toward each end thereof and ending in a flat annular face surrounding the ends of said tubular body structure and offset inwardly from each end of the tubular body structure for a distance substantially equal to the thickness of the aforesaid apertured plates, each of the projecting tubular ends of said spacer member being extended through the apertures in the apertured plates, and a tie bar projecting through said mold forms and through said tubular body structure for securing said mold forms together, said mold forms when separated from said spacer member operating to withdraw said apertured plates from the tubular ends of said spacer member and providing an annular hollow space in the molded material around the ends of said tubular body structure.

2. A mold structure as set forth in claim 1, in which said apertured plates are provided with resilient members encircling said plates which have a peripheral contour at their outer extremities 5 that conform with the shape of said flanges.

3. A mold structure as set forth in claim 1, in which the flat annular faces adjacent each end of said spacer member extend in planes substantially parallel with the plane of the inner 10 faces of the mold forms.
